UNITED STATES PATENT OFFICE.

FRANCIS G. CAMERON, OF HAMILTON, ONTARIO, CANADA, ASSIGNOR OF ONE-THIRD
TO JOHN RICHARDS AND ONE-THIRD TO HUGH L. HAYES, BOTH OF HAMILTON,
ONTARIO, CANADA.

STARCH-PRINTING DEVICE.

1,249,595.

Specification of Letters Patent. Patented Dec. 11, 1917.

Application filed September 13, 1916, Serial No. 119,952. Renewed October 18, 1917. Serial No. 197,351.

To all whom it may concern:

Be it known that I, FRANCIS G. CAMERON, a subject of the King of Great Britain, residing at Hamilton, in the county of Wentworth and Province of Ontario, Canada, have invented a new and useful Starch-Printing Device, of which the following is a specification.

My invention relates to improvements in devices for printing molds in starch, for the manufacture of candies, bonbons, and the like, and consists of, essentially, a frame, starch trays and a leveling device therefor, interchangeable molding boards adapted to be fixed to a vertically operative press, and provided with a multiplicity of teats for the purpose of effecting corresponding molds in the starch.

My invention has for its objects, to provide a device for more effectively and efficiently accomplishing this heretofore specified process in the manufacture of candy, in a substantial reduction of the time which was hitherto required for the same.

This object, together with other objects apparent to those skilled in the art, may be attained by the device illustrated in the accompanying drawing, in which:—

Figure 1 is a front elevation of the entire device, Fig. 2 is a side elevation of the same with the tray and table removed, Fig. 3 is an enlarged detailed side view of the hammer operating mechanism, on the line X—X in Fig. 1, and Fig. 4 is an enlarged detailed front view of the same.

Similar characters of reference refer to similar parts throughout the several views.

Reference being had to the accompanying drawing, the corner legs A, the longitudinal pieces B and C, together with two similar pieces which are behind the pieces B and C and therefore not seen in the drawing, and the transverse pieces D, E and F, with similar pieces at the opposite side of the device, constitute the framework of the machine.

The usual tray 2 of starch is positioned on a leveling device which comprises a horizontal table 3 supported by hand screws 4 which are threaded through the pieces B, and adapted to adjust the said table to a level position in the frame.

5 is the press secured at each end to a traveler 6 adapted to vertically operate between the posts A as illustrated in Fig. 2

of the drawing, by the means hereinafter to be set forth. The said travelers are provided with wheels 7 adapted to engage with the said posts, and therefore facilitate the sliding of the same.

A molding board 9 is fixed to the press 5, at 10 in Fig. 1 of the drawing, and is provided with a multiplicity of teats 12. A number of these molding boards are to be provided, having various shaped teats, depending upon the shape of the candy required, each said board to be fixed to the press, as desired.

A longitudinal shaft 13 is suitably journaled at its ends to bearings 14 on the transverse pieces D at each side of the machine, and has rigidly secured to its central part, a lever 15. Quadrant gears 16 are rigidly secured to each end of the shaft 13, and are adapted to mesh with corresponding vertical racks 17, which are rigidly secured to the top of the press 5.

The racks 17 are adapted to travel vertically in suitable guide tracks 18 secured to the top of the transverse pieces D, and it will be seen that motion delivered to the lever 15 in the direction indicated by the arrow, will cause the press 5, together with the molding board 9, to descend and to effect molds, corresponding to the teats 12, in the starch in the tray 2.

Counter weights 19 are secured to integral arms 20 radially extending from the respective quadrant gears 16, as shown in Fig. 2 of the drawing, for the purpose of automatically returning the press 5 to its previous position after it has performed its function.

A silk screen 22 is provided between the molding board 5 and the teats 12, for the purpose of taking up by adhesive means the surplus starch which is displaced by the entrance therein of the teats 12, and that which becomes pulverized by the impact of the molding board. The said starch perforates through said screen and rises through a plurality of apertures or slots 21 in the molding board 5, leaving perfectly smooth the surface of the starch in the tray 2.

An apparatus for jarring or agitating the press and molding board, while descending, in order to relieve it from starch which possibly adheres to it from its last operation, is provided as follows:

A cam 23 is rigidly secured to the shaft 13 110

in proximity to the lever 15, and is provided with a plurality of teeth 24, pivotally connected thereto in respective slots. 25 is a pawl rigidly secured, in alinement with the 5 cam 23, to one end of a shaft 26, which shaft is journaled in bearings 27 on a bracket 28. A hammer 29 is rigidly secured to the opposite end of the shaft 26, and is adapted to move simultaneously with the pawl 25. The said 10 hammer is tensioned against the top of the press 5 by means of spiral spring 30 fixed around the shaft 26 between the bearings 27.

When the press is operated, the teeth 24 contact in turn with the pawl 25, consequently 15 the hammer 29 effects slight, but substantial jars to the press, freeing the molding board from all starch adhering from the last operation. When the machine has performed its function, the press is returned 20 to its previous position by the means heretofore specified, and while returning, the teeth 24 while passing the pawl 25, move to the upper limits of their respective slots, and therefore effect no agitation to the press, leaving the tray of molded starch with a 25 smooth surface.

A hopper 31 is positioned in the frame, below the table 2, in order to receive and to preserve the waste starch from the different 30 trays, and 32 is a clean-out or exit for the said starch from the hopper.

I claim:

1. In a starch printing device, a frame, a table mounted in the frame and adapted to support a tray of starch, a vertically operative press in the frame above said table, a molding board fixed to the under side of said press and having a plurality of apertures or slots therein, a silk screen on the under side 35 of said molding board, a plurality of molding teats fixed to the under side of said molding board, vertical racks secured to the top of said press, guide means for said racks, a longitudinal, horizontal shaft journaled 40 at its ends to the top of each side of the frame, quadrant gears rigidly secured to said shaft and adapted to mesh with said racks on the press, a lever rigidly secured to the central part of said shaft, means for counter balancing said 45 press and molding board, a cam rigidly secured to said shaft, a plurality of teeth pivotally connected in respective slots to said cam, a shaft journaled in bearings on a bracket secured to the rear top part of the frame, a pawl rigidly secured to one end of said shaft and adapted to abut against said teeth, a hammer rigidly secured to the opposite end of said shaft and adapted to operate simultaneously with said pawl, and a spiral spring around said shaft between said bearings for the purpose of tensioning said hammer against the top of the press, for the 50 purpose specified.

2. In a starch printing device, a frame, a table mounted in the frame and adapted to support a tray of starch, a vertically operative press in the frame above said table, a molding board fixed to the under side of said press, a plurality of molding teats on the bottom of said molding board, vertical 55 racks secured to the top of said press, a horizontal shaft journaled at its ends to bearings on the top of each side of the frame, quadrant gears rigidly secured to said shaft and adapted to mesh with said racks on the press, a lever rigidly secured to the central part of said shaft, means for counter balancing said press and molding board, a cam rigidly secured to said shaft, a plurality of teeth pivotally connected in respective slots to said cam, a shaft journaled in bearings on a bracket secured to the rear top part of the frame, a pawl rigidly secured to one end of said shaft and adapted to abut against said teeth, a hammer rigidly secured to the opposite end of said shaft and adapted to operate simultaneously with said pawl, and a spiral spring around said shaft between said bearings for the purpose of tensioning said hammer against the top of the press, for the 60 purpose specified.

3. In a starch printing device, a frame, a table mounted in the frame and adapted to support a tray of starch, a vertically operative press in the frame above said table, a molding board fixed to the under side of said press and having a plurality of apertures or slots therein, a silk screen on the under side 65 of said molding board, a plurality of molding teats fixed to the underside of said molding board, means for operating said press, and means for automatically returning said press and molding board to their previous position.

FRANCIS G. CAMERON.
